[57] CLAIM

The ornamental design for a television stand for a van or the like, as shown and described.

DESCRIPTION

FIG. 1 is a perspective view of a television stand for a van or the like showing my new design, it being understood that the broken line showing of a television and a portion of the interior of a van is for illustrative purposes only;

FIG. 2 is a perspective view thereof;

FIG. 3 is a top plan view thereof;

FIG. 4 is a front elevational view thereof;

FIG. 5 is a right side elevational view thereof;

FIG. 6 is a left side elevational view thereof;

FIG. 7 is a rear elevational view thereof; and,

FIG. 8 is a bottom plan view thereof.

FIG. 3

FIG. 4

FIG. 5

FIG. 6

FIG. 7

FIG. 8
